UNITED STATES PATENT OFFICE.

WILLIAM LEO BAXTER, OF BEVERLY, MASSACHUSETTS.

DESIGN FOR A SHOE OR SIMILAR ARTICLE.

Application filed February 8, 1922. Serial No. 593. Term of patent 3½ years.

To all whom it may concern:

Be it known that I, WILLIAM LEO BAXTER, a citizen of the United States of America, residing at Beverly, in the county of Essex and Commonwealth of Massachusetts, have invented a new, original, and ornamental Design for a Shoe or Similar Article, of which the following is a specification, reference being had to the accompanying drawing, forming a part thereof.

In said drawing, Figure 1 is a perspective view of a shoe showing my new design; and Figure 2 is a cross sectional view through the toe portion of such shoe.

I claim:

The ornamental design for a shoe or similar article substantially as shown.

Signed by me at Boston, in the county of Suffolk and Commonwealth of Massachusetts, this 1st day of February, 1922.

WILLIAM LEO BAXTER.
